PHOTOCELL CONTROL FOR CUT-OFF
MECHANISM

Charles P. Barker, Glencoe, Ill.

Application September 8, 1932, Serial No. 632,108

6 Claims. (Cl. 164—68)

This invention relates to apparatus for automatically segmenting a continuous strip into uniform lengths or lengths bearing definite relationship to printed forms, designs, or other markings upon the surface of the material and making such compensations as may be necessary for variations in feeding the material. The novel features are especially desirable when used in combination with apparatus for forming a continuous strip bearing a series of designs thereon and used for making merchandise wrappers, for example wrappers for packing individual electric light bulbs and the like. It is in this connection that the invention has been illustrated.

While it has long been the practice to automatically cut a continuous strip of paper or the like into units of a given length, and at the same time to automatically regulate the feeding of the continuous web to compensate for expansion and contraction in the material of the strip under barometric influence, and for variations in slippage or other variations in feeding the web; correction by variation in the speed of the feeding of the web has several disadvantages, particularly when the material is of a nature which necessitates handling it delicately. In the case of corrugated boarding, for example, the pressure of the feed rolls on the web must be very light, with the result that the web slips easily and is sometimes slow to respond to speed changes of the feeding rolls. Even in the case of flat paper, changes of speed are quite likely to cause breakage, which would require re-threading the web through the machine.

The present invention aims chiefly to overcome such difficulties and to provide apparatus which will satisfactorily compensate for feeding variations when used for any material, even though it be a flimsy, easily torn paper or corrugated cardboard with the attendant problems of delicate handling.

Accordingly, the present invention proceeds upon the principle of operating the web forming and feeding apparatus as uniformly as possible and at the same time operating a periodic cutter substantially synchronously, but with automatic correction of its periodicity or speed to compensate for unavoidable variations in the feeding of the web. The automatic compensation may be accomplished by means of a minutely variable speed transmission controlled by suitable mechanism in response to impulses of an electric eye arranged to scan the moving web, though of course many other forms of compensation may be used. Such mechanism will increase or decrease

the periodicity of the cutter according as it intersects the web before or after the preferred locus of severance reaches the cutter.

With these and various other objects in view, the invention may consist of certain novel features of construction and operation, as will be more fully described and particularly pointed out in the specification, drawings and claims appended hereto.

In the drawings, which illustrate an embodiment of the device, and wherein like reference characters are used to designate like parts,

Figure 1 is a diagrammatic side view of the illustrated embodiment of the invention, indicating the circuits diagrammatically;

Figure 2 is a plan view of the structure shown in Figure 1; and

Figure 3 is a detailed illustration of one possible arrangement of the actuator.

Although my invention may take many forms, only one has been chosen for illustration. According to this form, a continuous web 10 of paper or corrugated cardboard or the like, is fed forwardly by feed rolls 12 which are suitably mounted in the frame 16 of the machine as a whole. This illustrated form contemplates the use of the apparatus shown in combination with a unit for forming a corrugated strip, folding it along longitudinal lines, and joining the folded over edges by gluing a strip of tape along these adjacent edges. To prevent crushing the corrugated boarding, the upper roll 12 is mounted in slidable bearing blocks 18 partially supported by springs 20, and limited as to downward movement by bolts 22. These rolls are preferably geared together by gears 24 and driven by a chain 26 which in turn is driven by sprocket 28 on shaft 30 driven directly by motor 32 through chain 34.

From the feed rolls the corrugated board web in the form of a folded tube is passed to the cutting apparatus which includes a cutting cylinder 36 carried by rotary cutter bar 38, and in which one or more cutting blades 39 may be mounted in any suitable manner. The blades 39 cut against a preferably smooth pressure roll 40, which is likewise mounted on the rotatable shaft 41. Either the pressure roll 40 or the cutter rod 38, or both, may be resiliently or adjustably mounted if desired, but they are preferably pressed toward each other by stiff springs and limited in this movement by suitable screws to prevent injury to the blades. The blades 39 should contact the pressure roll firmly, but the remainder of the cylinder 36 should be of sufficiently small radius not to contact the web, but to let it move freely.

Between the feed rolls 12 and the cutter mechanism, the web passes along a table 42 over which is mounted a scanning unit 43 which is slideable on suitable stationary bars 44 supported from the general frame 16 in any suitable manner. The scanning apparatus 43 may be shifted longitudinally of the web by the handle 45 by means of shaft 46 and gear 47 which rotates a worm 48 engaging threads on one of the bars 44. A scale 10 49 may be provided to aid in setting the scanning apparatus.

The cutter unit is driven by the motor 32 which drives shaft 30 as previously stated. This shaft 30 drives the variable speed transmission device 15 55, the primary cones 56 of which are splined on said shaft. A belt 57 engages these cones and also engages cones 58 splined to the shaft 59, which drives the chain 60, which in turn drives a sprocket 61 mounted idly on the shaft 41. A 20 clutch 63 is provided for engaging the shaft 41 to the sprocket 61. The clutch 63 is operated by a clutch fork 64 carried by a shaft 66, which is normally urged in a clutch engaging direction by a spring 67. The shaft 66 also carries a gear 25 68 keyed thereto, and may be rotated by a handle 69. The gear 68 is arranged to engage a gear 70 keyed on shaft 41 when the clutch 63 is disengaged. The gear 70 normally engages a gear 72 which is keyed to and rotates the cutter rod 30 38. The shaft 66 and gear 68 are provided chiefly for the purpose of initially setting the cutter rod to register with a design on the web in starting the machine.

An eccentric 74 is driven from the shaft 41 35 through a suitable gear box 76 carried by the frame in any suitable manner. Reciprocated by the eccentric 74 is the eccentric shaft 78 which, through a rotatably mounted bell crank lever 79 reciprocates a driving rod 80. The driving rod 40 80 oscillates a disk 82 which bears pawls 84 and 86 which are arranged to engage a ratchet wheel 88 when desired, being controlled in any manner described hereinafter. Ratchet wheel 88 which is prevented from unintentional rotation 45 by spring dog 89, turns the shaft 90, which through the gears 92 turns a shaft 93. The shaft 93 through right and lefthand threads, or in any other manner desired, adjusts speed changing levers 96 which are suitably pivoted as at 98 and 50 which adjust the cones 56 and 58. The details of the structure of the speed changing apparatus of which the cones 56 and 58 and the levers 96 and shaft 94 form a part, are shown diagrammatically or not at all, inasmuch as they are 55 well known and may be obtained as a unit on the open market. To permit manual adjustment when desired, the shaft 94 may be provided with a handle 100.

It should be understood that the corrugated 60 web 10, or more exactly speaking the flat paper on the top side thereof, will be printed with a suitable design, with which design it is desired that the cutter blade should register or coincide in some particular predetermined relation. Due to 65 variations in temperature and humidity, to slippage and to a variety of other causes, the machine once set to sever the web at the desired points will vary from the proper setting. More accurately it might be said that although the 70 machine remains constant, the web changes in length or varies from its original movement so that compensations in the machine are necessary. To aid in these compensations the design on the web 10 may include a transversely extending 75 mark preferably about one-sixteenth of an inch

wide (longitudinally of the web) and about three-eighths of an inch or more long (transversely of the web). These marks may coincide with the desired line of severance, or may bear some definite relation thereto. According to the present invention compensation is controlled through the use of an electric eye for scanning these marks, and by providing contact means to indicate when the knife severs the sheet. The electric eye is associated with these contact means and through suitable electrical apparatus sends an electrical impulse to the contact means when each of the marks passes the spot on which the electric eye is focused. If the mark is late in reaching said spot or in other words, if the cutter is too advanced, then the impulse is directed by the contact means, which may be called a distributor, to a retardation relay system, which causes a retardation of the cutter mechanism to correspond with the lagging of the mark on the web. On the other hand, if the mark passes under the eye in advance of the time it is due (i. e., if the cutter is lagging) the distributor sends the electrical impulse to another relay system for speeding up the cutter to correspond with the advanced position of the mark.

This compensation control is illustrated diagrammatically in Figure 1. The scanning apparatus 43 includes an electric light bulb 102 from which a beam is directed by a suitable shield 30 and lens structure 104 onto the moving web. Arranged to focus at the illuminated spot, is an electric eye unit 106 including a photo electric cell 108. When the light focused on the photo electric cell 108 is varied, the current passing 35 from the negative lead 110 thereof to positive lead 112 and return 113 is varied, its variation comprising an electrical fluctuation which, by means of a suitable amplifier indicated as a unit by numeral 114, causes an electrical impulse to 40 be transmitted from a negative lead 118 through wire 120. The unit 114 includes suitable tubes, transformers, power connections and the like for purposes described, though for simplicity of illustration these have not been shown.

The wire 120 is connected to a distributor unit 124. This distributor unit comprises a cam 126 mounted on or turned by shaft 38 and contact springs 128 and 129 which are both mounted on an adjustable plate 130 and arranged to normally bear against the cam 126. The cam 126 is so shaped that at one position only, namely the position shown in Figure 1, both of the contacts 128 and 129 are retracted. This position of cam 126 preferably corresponds to a cutting position of cutter rod 38. Adjustments may be made, however, by rotating the disk 130, for which purpose the screw 132 and return spring 134 are provided. Mounted on the disk 130 at a position to contact contact spring 128 when it is pressed 60 out by the cam 126, is a contact 136 which is connected to a wire 138 connected to a retarding relay system 140. Likewise mounted on disk 130 and positioned to contact the contact strip 129 when it is passed outward by the cam 126, is a 65 contact 142 which is connected through a wire 144 to an accelerating relay system 146. The relay systems 140 and 146 have not been shown by the usual relay symbol, since they may include amplifiers. Both of these relay systems are connected to a positive lead 147 connected to the same source as lead 118.

The relay system 140 when actuated closes a contact 148, which, through a separate circuit 150 energizes the coil 152. There is preferably pro- 75

vided a time switch 153 which shunts across contacts 148 to maintain this circuit closed a certain length of time (for example long enough to permit three strokes of the driving rod 80) and prevents its closure for some time, perhaps half a minute, thereafter. Energization of coil 152 draws its plunger rod 154 upwardly, swinging mask 155 out from under pawl 84, so that the latter is permitted to engage ratchet wheel 88 and rotate the same as plate 82 is oscillated by rod 80. Ratchet wheel 88, through gears 92 causes a rotation of shaft 94 in a direction to adjust the variable speed transmission unit 55 to a slower ratio, in order to slightly reduce the speed of the cutter bar 38.

In a similar manner the energization of relay system 146 closes contacts 158 to complete a separate circuit 160 which includes coil 162. This circuit is likewise held closed by a time switch 163 and then prevented from closing for a short interval. Coil 162 when energized draws up the plunger rod 164 which raises mask 165 out from under pawl 86, permitting the pawl to engage the ratchet wheel 88 and rotate it in the direction opposite to the direction in which it is rotated by pawl 84. Through gears 92 shaft 94 is thus rotated in a direction to shift the variable speed transmission 55 to a faster ratio in order to slightly speed up the rotation of the cutter bar 38.

The electrical units have not been shown in detail, since they may take a variety of forms already well known in the art relating to photo electric devices. It should be understood, of course, that the units which have been indicated would include such tubes, transformers, power units and other elements as may be necessary to cause an energization of the coils 152 and 162, as described.

Operation

In initially starting a machine, the web is fed through the machine and under the cutter cylinder 36 and adjusted in the correct position for severance. The shaft 66 is then pressed in, disengaging clutch 63, and the cutter blade is turned by hand to a cutting position. With the parts remaining stationary, the scanning unit 43 is then adjusted by handle 45 to a position at which the electric eye unit 106 is focused on one of the marks. The motor is then started and the machine is operated under power. As long as the marks continue to fall under the focus of the eye 106 at the same instant that the cutter blade severs the web, no adjustment is necessary and none is made. However, due to a variety of factors, the chief of which are slippage and shrinkage or expansion of the paper facing of the web 10, the web gradually departs from correct registry with respect to the cutter blade. In other words, it is found that at the instants of severance of the web by the blade, the marks either lag behind or run slightly in advance of the focus point of the electric eye 106. It follows that, under this condition, when the mark is under the focus of the electric eye the cutter is either advanced or lagging its proper timing.

Whenever any mark passes under the focus of the electric eye it causes a variation in the current flowing through the wire 112 to the amplifier 114. This variation causes an electrical impulse or potential to be transmitted through wire 120 to the distributor 124 and more specifically to the spring contacts 128 and 129. If the cutter rod 38 is in the cutting position at the time of this potential, i. e., when the mark is focused under

the electric eye, then the impulse is not transmitted, the spring contacts 128 and 129 being open. However, if when the impulse is initiated by the electric eye, the cutter blade is not in the correct position, then either contact 128 or contact 129 will be closed by the cam 126. If the cutter blade is relatively behind its correct timing, then the impulse will be transmitted from wire 120 through contacts 129 and 142, through wire 144 and to the relay system 146 to close contact 158 which, through circuit 160, will energize coil 162 and cause the shifting of the variable speed transmission unit 55 to speed up the cutter blade in order that it may catch up with its proper timing with respect to the marks.

On the other hand, if the cutter blade is relatively ahead of its proper timing at the instant of the impulse, the cam will have closed spring contact 128 on contact 136 so that the impulse sent over wire 120 by the electric eye 108 will be transmitted through contacts 136 and wire 138 to the retarding relay system 140 which will close contacts 148. The closing of these contacts will complete the circuit 150, thereby energizing coil 152 and causing the variable speed transmission unit 55 to be changed in the opposite direction to retard the rotation of the cutter blade, so that it may drop back to its proper timing with respect to the marks.

From the foregoing it is seen that the invention 30 contemplates the combination of a periodic cutter and a feed having a substantially constant drive adapted to feed the strips to said cutter, a minutely variable drive for said cutter and an automatic compensator for decreasing or increasing 35 the periodicity of the cutter according as the cutter intersects the strips before or after the preferred locus of severance reaches the cutter.

It is to be understood that many other embodiments of the invention, including some in improved form, will be apparent, and in the course of time more will be devised by those skilled in the art. It is not desired that this invention be limited to the details described, for its scope includes all such forms or improvements as come 45 within the spirit of the following claims.

What is claimed is:

1. Apparatus for segmenting a continuous strip in definite relation to a series of imprints upon the strip which includes: a periodic cutter; a feed having a substantially constant drive adapted to feed the strip to said cutter; a minutely variable drive for said cutter; automatic compensating means responsive to contrasting surface characteristics of a strip, located in definite relation to the cutter, and decreasing or increasing the periodicity of the cutter according as its intersection of the strip occurs before or after a predetermined preferred locus of severance reaches the cutter, said compensating means comprising electric eye apparatus for initiating an electric impulse when a given portion of the design passes into the focus of said electric eye apparatus; and a distributor comprising two independent contacts and a cam rotated with respect thereto by said cutter and shaped to open both of said contacts when in one predetermined position, to close one contact when on one side of said position and the other contact when on the opposite side of said position, said contacts being connected to transmit said electric impulse to a retarding relay system and an accelerating relay system respectively.

2. Apparatus for segmenting a continuous strip in definite relation to a series of imprints upon

the strip which includes: a periodic cutter; a feed having a substantially constant drive adapted to feed the strip to said cutter; a minutely variable drive for said cutter; automatic compensating 5 means responsive to contrasting surface characteristics of a strip, located in definite relation to the cutter, and decreasing or increasing the periodicity of the cutter according as its intersection of the strip occurs before or after a predetermined preferred locus of severance reaches 10 the cutter, said compensating means comprising electric eye apparatus for initiating an electric impulse when a given portion of the design passes into the focus of said electric eye apparatus; and 15 a distributor comprising two independent contacts and a cam rotated with respect thereto by said cutter and shaped to open both of said contacts when in one predetermined position, to close one contact when on one side of said position and the other contact when on the opposite side of 20 said position, said contacts being connected to transmit said electric impulse to a retarding relay system and an accelerating relay system respectively, said systems being arranged to cause the 25 adjustment of said drive in a retarding and accelerating direction respectively.

3. Apparatus for segmenting a continuous strip in definite relation to a series of imprints upon the strip which includes: a periodic cutter; a feed 30 having a substantially constant drive adapted to feed the strip to said cutter; a minutely variable drive for said cutter; automatic compensating means responsive to contrasting surface characteristics of a strip, located in definite relation to the cutter, and decreasing or increasing the periodicity of the cutter according as its intersection of the strip occurs before or after a predetermined preferred locus of severance reaches 35 the cutter, said compensating means comprising electric eye apparatus for initiating an electric impulse when a given portion of the design passes into the focus of said electric eye apparatus; and a distributor comprising two independent contacts and a cam rotated with respect thereto by 40 said cutter and shaped to open both of said contacts when in one predetermined position, to close one contact when on one side of said position and the other contact when on the opposite side of 45 said position, said contacts being connected to transmit said electric impulse to a retarding relay system and an accelerating relay system respectively, said systems being arranged to cause the 50 adjustment of said drive in a retarding and accelerating direction respectively by means of an oscillating member having a pair of pawls oppositely disposed thereon and arranged to engage ratchet members alternatively under influence of said relay systems.

4. Apparatus for segmenting a continuous strip in definite relation to a series of imprints upon the strip which includes: a periodic cutter; a feed having a substantially constant drive adapted to feed the strip continuously to said cutter; a minutely variable drive for said cutter; adjustment means for said variable drive, automatic compensation control means for operating said adjustment means responsive to contrasting surface characteristics of a strip, located in definite relation to the cutter, and decreasing or increasing the periodicity of the cutter according as its intersection of the strip occurs before or after a predetermined preferred locus of severance reaches 60 the cutter, said compensation control means comprising electric eye apparatus for initiating an electric impulse when a given portion of the design passes into the focus of said electric eye apparatus; and a distributor comprising two independent contacts and a cam rotated with respect thereto by 65 said cutter and shaped to open both of said contacts when in one predetermined position, to close one contact when on one side of said position and the other contact when on the opposite side of 70 said position, said contacts being connected to transmit said electric impulse to a retarding relay system and an accelerating relay system respectively, said systems being arranged to cause the 75 adjustment of said drive in a retarding and accelerating direction respectively by means of an oscillating member having a pair of pawls oppositely disposed thereon and arranged to engage ratchet members alternatively under influence of said relay systems.

5. Apparatus for segmenting a continuous strip in definite relation to a series of imprints upon the strip which includes: a periodic cutter; a feed having a substantially constant drive adapted to feed the strip continuously to said cutter; a minutely variable drive for said cutter; adjustment means for said variable drive, automatic compensation control means for operating said adjustment means responsive to contrasting surface characteristics of a strip, located in definite relation to the cutter, and decreasing or increasing the periodicity of the cutter according as its intersection of the strip occurs before or after a predetermined preferred locus of severance reaches the cutter, said compensation control means comprising detecting apparatus for initiating an electric impulse when a given portion of the design passes into the focus of said electric eye apparatus; and a distributor controlled by the cutter for nullifying said impulse if it occurs when said cutter is properly timed, and for transmitting it to a retarding relay system if said cutter is in advance of its proper time and to an accelerating relay system if said cutter unit is lagging behind its proper time, said systems being arranged to cause the operation of said adjustment means in a retarding and accelerating direction respectively by means of an oscillating member driven continuously by one of said drives and having a pair of pawls oppositely disposed thereon and arranged to engage ratchet members alternatively under influence of said relay systems.

6. Apparatus for segmenting a continuous strip in definite relation to a series of imprints upon the strip which includes: a periodic cutter; a feed having a substantially constant drive adapted to feed the strip continuously to said cutter; a minutely variable drive for said cutter; adjustment means for said variable drive, automatic compensation control means for operating said adjustment means responsive to contrasting surface characteristics of a strip, located in definite relation to the cutter, and decreasing or increasing the periodicity of the cutter according as its intersection of the strip occurs before or after a predetermined preferred locus of severance reaches the cutter, said compensation control means comprising detecting apparatus for initiating an electric impulse when a given portion of the design passes into the control of said detecting apparatus; and a distributor controlled by the cutter for nullifying said impulse if it occurs when said cutter is properly timed, and for transmitting it to a retarding relay system if said cutter is in advance of its proper time and to an accelerating relay system if said cutter unit is lagging behind its proper time, said systems being arranged to cause the operation of said adjustment means in a retarding and accelerating direction respectively by means of an oscillating member driven continuously by one of said drives, and a member driven thereby in alternative directions through ratchet-like means operable in either direction alternatively under influence of 30 said relay systems.

7. Apparatus for segmenting a continuous strip in definite relation to a series of imprints upon the strip which includes: a periodic cutter; a feed having a substantially constant drive adapted to feed the strip continuously to said cutter; a minutely variable drive for said cutter; adjustment means for said variable drive, automatic compensation control means for operating said adjustment means responsive to contrasting surface characteristics of a strip, located in definite relation to the cutter, and decreasing or increasing the periodicity of the cutter according as its intersection of the strip occurs before or after a predetermined preferred locus of severance reaches the cutter, said compensation control means comprising detecting apparatus for initiating an electric impulse when a given portion of the design passes into the control of said detecting apparatus; a distributor controlled by the cutter for nullifying said impulse if it occurs when said cutter is properly timed, and for transmitting it to a retarding relay system if said cutter is in advance of its proper time and to an 70 accelerating relay system if said cutter unit is lagging behind its proper time, said systems being arranged to cause the operation of said adjustment means in a retarding and accelerating direction respectively by means of an oscillating member driven continuously by one of said drives, and a member driven thereby in alternative directions through ratchet-like means operable in either direction alternatively under influence of 75 said relay systems.

accelerating relay system if said cutter unit is lagging behind its proper time; and driving means arranged to be driven by one of said drives and arranged to drive said adjustment means, and including two alternatively active members, one of which may be made active by the accelerating relay system to cause said driving

means to operate said adjusting means in an accelerating direction, and the other being controllable by said retarding relay system to cause said driving means to drive said adjustment means in the retarding direction. 5

CHARLES P. BARKER.
